THREAD CUTTING CHASER

Albert F. Breitenstein, New Haven, Conn., assignor to The Geometric Tool Company, New Haven, Conn., a corporation of Connecticut

Application June 1, 1936, Serial No. 82,717

6 Claims. (Cl. 10—103)

This invention relates to improvement in chasers for cutting threads on various objects, such for instance as upon rods, tubes, etc.

In mass-production thread-cutting practice it is customary to engage a plurality of chasers with the article to be threaded. This practice often, especially in producing coarse-pitch threads, causes the mutilation of the starting-portion of the thread formed by the front tooth of the particular chaser or chasers which first contact the work with a full or nearly-full cutting-tooth before a full or nearly-full cutting-tooth of the succeeding or tracking chaser or chasers can contact the article and stabilize the cutting action.

The main object of the present invention, therefore, is to provide a thread-cutting chaser which will obviate the thread mutilation above referred to.

With the above and other objects in view, as will appear to those skilled in the art from the following, considered in conjunction with the accompanying drawing and appended claims, the present invention includes all features disclosed therein which are novel over the prior art.

In the accompanying drawing:

Fig. 1 is a face view of a die-head upon which are mounted four chasers, two of which embody the present invention;

Fig. 2 is a broken sectional view on an enlarged scale, taken on the line 2—2 of Fig. 1;

Fig. 3 is a face view of a circular chaser embodying the present invention;

Fig. 4 is an edge view thereof;

Fig. 5 is a face view of a toothed blank from which a chaser embodying the present invention may be formed;

Fig. 6 is an edge view thereof;

Fig. 7 is a face view of the blank after the same has been chamfered;

Fig. 8 is an edge view thereof;

Fig. 9 is a face view of the blank after the same has been provided with a checking-shoulder; and

Fig. 10 is an edge view thereof.

Prior to the detailed description of the improved chaser, attention is called to the showing in Fig. 1, in which a die-head 20 of any approved construction carries four (more or less) radially-movable chaser-carriers 21, upon each of which is mounted a so-called "circular chaser." The four chasers referred to are designated respectively as A, B, C, and D, and of which the chasers A and C correspond to each other as do also the chasers B and D. The two chasers B

and D referred to embody the present invention, while the chasers A and C are of usual form.

For purposes of description, it may be assumed that the chasers A, B, C, and D of the die-head 20 are designed and arranged to cut double threads upon a $\frac{3}{4}$ " rod. Let it further be assumed that the threads to be produced are of $\frac{1}{8}$ " pitch and, therefore, have a $\frac{1}{4}$ " lead owing to the thread being double.

Under these conditions, the chasers A and B 10 cooperate in producing one of the double threads and the chasers C and D similarly cooperate in producing the other of the double threads referred to.

Each of the chasers A, B, C, and D is formed 15 upon its periphery with a series of circumferentially-extending thread-cutting teeth 22, each of which terminates in a cutting-lip 23 forming one end of a cut-away portion 24 of each of the otherwise cylindrical chasers. For its attachment to one of the radially-movable chaser-carriers 21, each chaser is formed with an axial passage 25 for the reception of suitable fastening-means.

Each of the chasers A, B, C, and D is formed 25 with a chamfer 26 which facilitates the initial engagement of the chasers with the work 27 indicated in Fig. 2. It will be noted by reference to Fig. 2 in particular that the chamfer 26 of the chaser D extends up onto the advance face of the 30 front tooth 22^a thereof.

It is to be here noted that the descriptive matter relating to the chaser D applies with equal force to the chaser B, and similarly that the descriptive matter relating to the chaser C applies with equal force to the chaser A.

The chaser C is the tracking chaser, so to speak, of the chaser D and, therefore, has its cutting-teeth 22 located in line with the gaps between the cutting-teeth of the chaser D and 40 hence the formation of the chamfer 26 of the chaser C results in leaving on the said chaser a very incomplete front tooth 22^b.

The advance face of the front tooth 22^a of each of the chasers B and D is cut away to provide a 45 checking-shoulder 28 which intersects the chamfer 26, as clearly shown in Fig. 2. The important point about the checking-shoulder 28, just referred to, is that it is located from the back or trailing face of the tooth 22^a a distance represented by the dimension E (Fig. 2) which is less than the dimension F representing the normal root thickness of the cutting-teeth 22. For purposes of comparison, broken lines 22^c have been applied to Fig. 2 adjacent the tooth 22^a to 55

indicate what would be the normal shape of the said tooth were it not for its being cut away to form the chamfer 26 and the checking-shoulder 28.

5 One mode of producing chasers embodying the present invention comprises forming a cylindrical blank such as is shown in Figs. 5 and 6 with annular ribs having a cross-sectional form corresponding to the desired cross-sectional form of 10 the desired thread-cutting teeth 22. The blank may now be provided on its forward face with the chamfer 26 as shown in Figs. 7 and 8, after which the appropriate portion of the chamfer may be cut away to provide the checking-shoulder 28 as shown in Figs. 9 and 10. The said checking-shoulder preferably has a slope corresponding to the slope of the advance face of the teeth 22. After the blank has reached the stage shown in Figs. 9 and 10, a portion of its periphery is cut 20 away as at 24 to provide the desired cutting-lip 23 as shown particularly well in Fig. 3.

By reference to Fig. 2, it will be seen that the checking-shoulder 28 of the chaser D contacts the work before the first substantially-full 25 tooth 22^d of the chaser C, which latter complements the chaser D in cutting a given thread. The checking-shoulder 28 then serves to assist in stabilizing the cutting action of the group of 30 chasers and minimizes the tendency of the teeth 30 of one chaser to unduly advance or hold back with respect to the teeth of another chaser, so that the mutilation of the starting portion of the threads upon the work 27 is avoided.

In the above description and in the accompanying 35 drawing only so-called "circular" chasers have been shown and described, but it will be obvious to those skilled in the art that the invention may be applied to other well-known types of chasers.

40 From the foregoing, it will be seen that the front tooth of the chaser D, as well as the chaser B, is provided with a checking-shoulder 28, which is located from the back face of the said tooth a distance less than the root thickness of the other 45 thread-cutting teeth 22 of the said chaser. Many theories may be advanced as to the exact functioning of the checking-shoulder 28, but it is sufficient to state that when the said shoulder is located as above described with reference to the 50 back face of the particular tooth upon which it is formed, it serves to overcome the mutilation of the starting portion of threads formed upon rods and the like.

The invention may be carried out in other 55 specific ways than those herein set forth without departing from the spirit and essential characteristics of the invention, and the present embodiments are, therefore, to be considered in all respects as illustrative and not restrictive, and all 60 changes coming within the meaning and equiva-

lency range of the appended claims are intended to be embraced therein.

I claim:

1. A thread-cutting chaser having a plurality of thread-cutting teeth, including a front thread-cutting tooth, offsetting therefrom; the said front tooth having its advance face chamfered and also having a further portion of its advance face cut away to provide a checking-shoulder intersecting and extending at an angle to the chamfered 10 portion of the tooth.

2. A thread-cutting chaser having a plurality of thread-cutting teeth, including a front thread-cutting tooth, offsetting therefrom; the said front tooth having its advance face chamfered and also having a further portion of its advance face cut away to provide a checking-shoulder extending substantially parallel with the advance face of the other of said thread-cutting teeth.

3. A thread-cutting chaser having a plurality of thread-cutting teeth, including a front thread-cutting tooth, offsetting therefrom; the said front tooth having its advance face chamfered and also having a further portion of its advance face cut away to provide a checking-shoulder located 25 from the trailing-face of the said front tooth a distance less than the root-thickness of the other of said thread-cutting teeth.

4. A thread-cutting chaser having a plurality of thread-cutting teeth, including a front thread-cutting tooth, offsetting therefrom, the said front tooth having its advance face chamfered and also having a further portion of its advance face cut away to provide a checking-shoulder extending 30 substantially parallel with the advance face of the other of said thread-cutting teeth and located from the trailing-face of the said front tooth a distance less than the root-thickness of the other of said thread-cutting teeth.

5. A circular thread-cutting chaser having a plurality of peripherally-extending thread-cutting teeth offsetting therefrom, including a front peripherally-extending thread-cutting tooth; the said front tooth having its advance face chamfered and also having a further portion of its advance face cut away to provide a checking-shoulder intersecting and extending at an angle to the chamfered portion of the tooth.

6. A circular thread-cutting chaser having a plurality of peripherally-extending thread-cutting teeth offsetting therefrom, including a front peripherally-extending thread-cutting tooth; the said front tooth having its advance face chamfered and also having a further portion of its advance face cut away to provide a checking-shoulder located from the trailing-face of the said front tooth a distance less than the root-thickness of the other of said thread-cutting teeth.

ALBERT F. BREITENSTEIN.
